(No Model.)

M. MAGINN.
SPEED REGULATING DEVICE.

No. 433,529.

Patented Aug. 5, 1890.

Madison Maginn

UNITED STATES PATENT OFFICE.

MADISON MAGINN, OF CHICAGO, ILLINOIS.

SPEED-REGULATING DEVICE.

SPECIFICATION forming part of Letters Patent No. 433,529, dated August 5, 1890.

Application filed September 5, 1889. Serial No. 323,098. (No model.)

To all whom it may concern:

Be it known that I, MADISON MAGINN, a citizen of the United States, residing at Chicago, in the county of Cook and State of Illinois, have invented a new and useful Improvement in a Speed and Power Regulating and Governing Device, to operate in conjunction with a water-power-developing device, for which I have made a separate application, 5 Serial No. 296,777, filed January 18, 1889. This governing device is a part of said water-power-developing device and original invention as set forth in my application as above referred to; and I do declare the following, when taken 10 in connection with the drawings and the letters of reference marked thereon, to be a full, clear, and exact description of my device, and of which the following is a specification.

My invention relates to improvements in a 20 device for regulating and governing the power and speed of a water-power-developing device in which a hydraulic or other suitable cylinder is arranged to operate a traveling frame or carriage, with a water motor or wheel 25 fixed thereon, same as represented in my application Serial No. 296,777, whereby the said water wheel or motor is regulated in depth of contact with the falling water and the 30 speed and power of said wheel or motor are regulated and governed by this governing device; and the objects of my invention are, first, to provide ways and means whereby a 35 hydraulic cylinder and piston operating and controlling the power and speed of a water wheel or motor can be controlled and governed and the speed regulated either automatically 40 or at the will of the operator; second, to provide ways and means whereby the piston of a cylinder operated by pressure and operating or controlling the power and speed of a 45 water wheel or motor in contact with and being driven by the weight and current of a body of falling water can be operated, controlled, and governed automatically or at the will of the operator; third, to provide ways 50 and means whereby the piston of a hydraulic cylinder operated by pressure may be automatically governed or regulated, or governed and regulated at the will of the operator. I 55 attain these objects by the mechanism illustrated in the drawings, in which—

Figure 1 is a side elevation of a hydraulic

cylinder with my automatic governing device attached thereto. Fig. 2 is an end elevation of said cylinder and my governing device attached thereto. Fig. 3 is an elevation, part sectional, of a six-way governing-valve for controlling the supply and exhaust outlets to and from a hydraulic or pressure cylinder. Fig. 4 is a sectional view of the governing-valve taken on the dotted lines $x\ x$ of Fig. 3. Fig. 5 is a sectional view of the governing-valve taken on the dotted lines $z\ z$ of Fig. 3. Similar letters refer to similar parts throughout the several views.

The cylinder D, as here shown, represents the cylinder of a water-power-developing device, detached for the purpose of clearly illustrating my regulating and governing device. Attached to the cylinder D is the governor J, 70 of well-known construction, connected to and operating the valve K, controlling the inlet of the supply-pipe.

K^2 is the supply-pipe receiving its supply from a steam force-pump located at any convenient distance and direction from the device. (Not here shown.) Said supply-pipe, having its connection to the valve K at K^2 , passes through the open slot in plug N and is conveyed into the cylinder D through the pipes 75 D^5 . K^3 , being the exhaust-pipe, leads the supply out and away from the cylinder D after it has entered the same. This regulating-valve K is constructed upon the principle of a six-way cock or rotary valve, M being the 80 barrel with the different openings and pipe-connections upon its sides at D^6 , D^6 , K^2 , and K^3 , &c., as shown. The plug N of the valve K, being a single piece and moving assuch, is so constructed and arranged that the different openings, as D^5 K^2 D^5 , inlet-slots of the plug N, will, when placed in the barrel M, cover but one of the openings D^5 of the barrel and retain a direct and open communication with the other openings D^5 and K^2 of the barrel 85 M at one and the same time. A like arrangement with the same construction is employed in the slots or openings D^6 K^3 D^6 of the exhaust portion of the plug N; but a difference of location in the plug becomes necessary, this difference being shown in dotted lines in Fig. 4 and open lines in Fig. 5. The necessity of this arrangement of openings in the plug is 90 apparent from the fact that when the pressure

is admitted to the rear of the cylinder and forces the piston-rod outward the exhaust-slot D^6 in plug N of the valve K must be open to permit the escape of the exhaust at K^3 .
 5 The action of the valve is the same in its reversing-movement, D^5 being the supply-pipe feeding the cylinder D and located in a parallel line along the cylinder, and D^6 the exhaust-pipe located close by and in a like manner to D^5 . Therefore when the supply in D^5 is let in at one end of the cylinder D the exhaust D^6 must be open at the opposite end of the cylinder, and vice versa for the opposite movement of the piston. This is accomplished by the arrangement of the slots in the plug N and the openings in the barrel M of the valve K , as shown in elevation and details, Figs. 3, 4, and 5. Projecting through the end of the valve-casing M , at N^2 , is the stem of the plug N . Upon this stem, at N^2 , is placed an operating-lever N^3 , which can either be operated by hand or automatically by the governor J . For operating the valve by the governor a connection is made to the operating-lever J^4 of the governor by the rod N^5 , one end of which is connected to one of two arms fixed at right angles upon a pivoted rocking sleeve N^4 . Said arms have an alternating movement given by the governor J through its connection to a rocking sleeve operating upon a stud prepared for this purpose. One of these alternating arms is connected to the operating-lever N^3 of the valve K , as shown in Figs. 1 and 2. When the governor transmits its alternating movement to the connections described, it is the means of operating the valve K , as will be further explained in the description of the governor. I have shown here connected to the valve and cylinder of my device the ordinary governor, consisting of two heavy balls suspended by links from a spindle, and caused to revolve, either by belt or shaft connection, with the shaft of the motor. In the drawing, the governor is driven by belt-connection to the pulley J^2 , bevel-gearred to the governor. When at rest, the balls hang close to the spindle, but when in motion the balls rise by centrifugal force. When the motor is running at its established speed, the links assume a position nearly at forty-five degrees with the spindle. If the speed falls, the balls fall, and acting on the lever J^4 (shown in side view) open the valve

K, controlling the passage-way to the cylinder D . If the speed rises, the balls rise and close the valve or act directly upon its equivalent, thus operating the valve K automatically. The lever J^4 may be connected direct to the valve K by placing the valve K in a horizontal position at the top of the cylinder D , instead of at the side, as is now represented, and changing the pipe-connections to cylinder to conform with this changed position of the valve. Then place the governor J in position above the valve, so that the lever J^4 and rod N^5 connect direct with the valve-lever N^3 . This arrangement simplifies and does away with the stud and pivoted sleeve with the stationary arms fixed at right angles upon the same. 7c

I am aware that prior to my invention governing devices have been made whereby piston and lift valves are operated by a stroke movement and operating in conjunction with elevator-hoists, &c. To this method I do not lay any claims. 75

What I do claim, and desire to secure by Letters Patent, is—

1. The combination, in a governing device, of a single rotary governing-valve having six ways or passages therein opening alternately to the flow of pressure and controlling simultaneously both the supply and exhaust passages conveying the pressure to and from the piston of a cylinder, a governor operated by a motor and connected to said valve arranged and adapted to operate said valve automatically, thus controlling the action of a piston within a cylinder, substantially as and for the purposes specified. 90

2. In a governing device, the combination, of a six-way rotary valve K , with its outside casing or barrel M , arranged and provided with six openings D^5 D^6 K^2 K^3 , &c., three of these openings being exhaust-outlets and three being supply-inlets, a rotary plug N , with its slots or openings in the same, arranged to operate and regulate the supply and exhaust, a governor J , with its operating-lever J^4 , connections N^3 N^4 N^5 to and operating the valve K , substantially as and for the purposes specified. 95 100

MADISON MAGINN.
